UNITED STATES PATENT OFFICE.

EDWARD W. BURGESS, OF MILWAUKEE, WISCONSIN, ASSIGNOR TO A. O. SMITH CORPORATION, OF MILWAUKEE, WISCONSIN, A CORPORATION OF NEW YORK.

MACHINE FOR PICKLING METAL PLATES AND BLANKS.

Application filed March 30, 1922. Serial No. 548,268.

To all whom it may concern:

Be it known that I, EDWARD WESLEY BURGESS, a citizen of the United States, residing in the city of Milwaukee, in the county of Milwaukee and State of Wisconsin, have invented a certain new and useful Improvement in Machines for Pickling Metal Plates and Blanks; and I do declare the following specification to be a full, clear, and exact description thereof, such as will enable persons skilled in the art to which the invention pertains to make and use the same, reference being had to the accompanying drawings for disclosure as to the construction of the apparatus.

The invention relates to a machine for pickling sheet metal plates or blanks, it being the function of the pickling operation to clear such plates or blanks from scale or other substances which may be injurious to the tools of the machines or presses which are used in shearing, punching, drawing, or otherwise treating the plates or the blanks cut therefrom, in the subsequent manufacturing operations.

The purpose of the invention is the provision of mechanical apparatus for effecting an operation heretofore generally performed by hand. By the use of such apparatus, we are enabled to avoid many of the disagreeable results incident to the personal contact of the workmen with the acid baths and the coated plates or blanks, as the latter are withdrawn from the baths.

The invention comprises a construction by means of which an endless conveyor carries the plates or blanks into and out of the several baths or vats used in the pickling process, and holds them submerged until all have been subjected to the desired treatment.

The invention is embodied in a structure in which the plurality of baths or vats containing the several chemical solutions are arranged in line or succession, and in connection with which an endless chain conveyor is employed to carry the plates or blanks from one bath to another, until such plates have received the necessary treatment by immersion in all of the baths.

In my improved construction the endless conveyor travels about and is actuated by driven sprocket wheels at each end of the apparatus. The endless conveyor moves over a substantially horizontal track way at

the upper portion of the apparatus, but the lower track way over which the conveyor moves is constructed with depressions in certain sections, whereby the endless conveyor is made to partake of an undulating movement while the plates or blanks are being treated. The depressions in the lower run of the track way are located immediately over the baths, while the high points between the depressions are positioned above the meeting or abutting ends of the contiguous baths. In this manner the metal plates or blanks supported by the conveyor will be lowered into the first bath and will be raised at the end of their movement through the first bath so as to clear that bath and be lowered into the next one, and so on.

The construction and arrangement is such that in the operation of the mechanism, the metal hooks supported by the endless conveyor and which carry the plates or blanks are the only parts of the apparatus, aside from the containing vats, which are subject to contact with the chemicals. These hooks are formed from a metal which will enable them to resist the action of the acids. The conveyor chains from which the hooks are suspended, are supported and guided in a line of travel which is clear of the vats or baths. By this construction and arrangement, the injurious effects of the acids upon the apparatus is avoided.

The invention resides specifically in the peculiar formation of the said hooks or hangers whereby they are adapted to support the plates and blanks at their lower edges only and in such manner that the plates and blanks will be free to have a slight rocking movement on their lower supporting edges, so that the whole surfaces of the plates and blanks may be subjected to the action of the solutions in the pickling operation. The hooked end of the hanger is returned so as to lie in substantial parallelism with the vertical shank thereof, and each of the parts is provided with an inwardly extending projection, which together form contacting points for the opposite sides of the plate or blank. The latter therefore is engaged by the hanger in such restricted areas of contact, and with such interrupted and slight pressures, that the entire surface of the plate or blank is efficiently treated in its passage through the baths or vats.

The features which constitute my present invention, will be defined in the claims appended hereto.

Referring to drawings accompanying this specification:

Figure 1 is a view in elevation showing in conventional manner the arrangement of the elements and the course of the main conveyor through the pickling apparatus.

10 Fig. 2 is a view in vertical cross section on the line 2—2, Fig. 1, in a plane intersecting the path of travel of the conveyor, showing one of the carriers of the conveyor with a metal plate in position thereon for treatment.

15 Fig. 3 is an enlarged view in side elevation of the apparatus, broken out at the center to save space.

20 Fig. 4 is a fragmentary view of the conveyor, on the scale of Fig. 3, and showing a section of the undulating track way, whereby the carriers for the plates are raised out of one bath preparatory to their immersion in another, one of the baths being shown in section.

25 Fig. 5 is a detail view showing the hook of special form which is employed to support a metal plate or blank while being conveyed through the pickling apparatus.

30 The invention herein presented is disclosed in an application Serial No. 355,727, filed jointly by R. Stanley Smith and me on February 2, 1920, and patented September 12, 1922, No. 1,428,716. The said patent also

35 discloses feeding mechanism for supplying plates to the endless conveyor for the pickling operation, and delivery mechanism for removing the plates from the endless conveyor at the conclusion of the pickling operation, as well as other features of construction associated with the apparatus as a whole.

40 In the drawings which accompany the present specification, the frame of the apparatus is indicated by the numeral 10. The sprocket wheels 11 are mounted upon a shaft 12, journaled in bearings in the left hand or feeding end of the frame, and sprocket wheels 13 are mounted upon a shaft 14, journaled in bearings at the right hand or delivery end of the frame. An endless conveyor 15 is supported upon and actuated by the sprocket wheels 11 and 13. In the present construction, the driving shaft 16 is located at the right hand end of the apparatus, as indicated in Fig. 3, and by means of the train of gears there shown, acts to drive directly the sprocket wheels 13. Motion is transmitted from the driving shaft 16 through a longitudinal shaft 17 to another train of gears at the left hand end of the apparatus, whereby the sprocket wheels 11 are driven, the said sprocket wheels 11 and 13 operating in synchronism.

45 In its forward movement, as indicated by

the arrow in Fig. 3, the upper run of the endless carrier passes over a substantially horizontal trackway 18, but the lower trackway 19 deviates from the horizontal for a part of its course, for a purpose which will be hereinafter described.

50 The apparatus is provided with a suitable number of baths or vats 20, adapted for the reception of the various liquids and chemicals used in the pickling operation. The baths 20 are arranged end to end in a ventilated housing 21, so constructed that the noxious gases will be discharged into the atmosphere. The course of the endless conveyor is through the several housings, as indicated in Fig. 1.

55 The lower trackway is provided with depressions extending alongside of the several baths, with intervening elevations at the points where the ends of the baths approach each other. The purpose of this construction is to impart to the endless carrier while moving through the apparatus, an undulating motion which will lower the metal plates or blanks supported by the conveyor into the respective baths, and after immersion for a suitable time remove the plates or blanks therefrom. The arrangement whereby such undulating movement of the conveyor is produced is indicated conventionally in Fig. 1. Fig. 4 shows some of the details of construction whereby such undulating motion is effected.

60 The endless conveyor 15 is formed as a chain, the links 22 of which are connected at their meeting ends by the pintles of rollers 23 which operate over the trackways 18 and 19. Guiding strips 24 are arranged above and spaced from the lower trackway 19, so as to insure proper movement of the carrier, by holding the rollers 23 in engagement with the trackway 19, as in the manner indicated in Fig. 4.

65 The endless conveyor is formed of two chains, one at each side of the apparatus, and connected laterally by bridge pieces 25, extending across the baths. The bridge pieces 25 support at their under sides a plurality of transversely arranged bars 26, having a length approximately equal to that of the links 22 of the conveyor. In Fig. 2, I have shown three of such transverse bars 26 distributed along the under side of the bridge piece 25. The said bars 26 may conveniently be formed as short sections of angle bars with one flange bolted in position against the under side of the bridge. The said angle bars may be grouped as indicated in Fig. 2. Depending hangers 27 are pivoted at their upper ends in the space between the vertical flanges of the pair of bars constituting each group.

70 The form of the hangers 27 is indicated in detail in Fig. 5. The function of the depending hangers 27 is to support the metal

plates or blanks 28 while the latter are being conveyed through the apparatus during the pickling operation. The movement of the endless conveyor is at all times in a plane 5 above that of the top of the baths, and by means of the depending hangers 27 the plates supported thereby are lowered into the baths, held therein a time sufficient to receive the necessary treatment, and then 10 moved therefrom. The hangers 27 are the only parts of the apparatus which enter the solutions contained in the baths. These hangers are made of bronze or some other acid resisting metal. The hanger is 15 provided with a hook at its lower end, which hook is adapted to receive and retain the metal plate or blank when the same has been supplied thereto, and in order that the area of contact between the hook and the metal 20 plate or blank may be reduced as much as possible, the said hangers are provided with contact points adapted to engage opposite sides of the metal plate or blank in the manner shown in Fig. 5. This construction 25 of the hanger leaves practically the whole surface of the blank free for action by the chemicals thereon. In actual practice the blank will contact with the hanger 27 at but two points, one being by reason of the engagement of the lower end of the plate with the hooked end of the hanger, and the other with one of the opposed points, depending 30 upon the angular position of the blank with relation to the hanger.

35 The hangers 27 employed by me are of peculiar construction, and are especially designed for the attainment of the most efficient results. Such hangers are in the form of pendants, returned at the lower end to 40 form a hook 27^a which lies substantially parallel with the main portion of the hanger, and thus support the plate 28 in substantially vertical position. The free point of the hook is provided with a projection or barb 27^b, which extends inwardly so 45 as to contract the space between the hanger and the hook. An oppositely extending projection 27^c on the face of the hanger 27 is arranged for co-operation with the projection 27^b in reducing to a minimum the area 50 of engagement of the hanger with the plate 28. The plate is deposited upon the aligned hangers with its lower edge resting in the necks of the hooks, and engaging the barbs 55 and projections of the hangers, alternately, inasmuch as the spacing of the barbs and projections from the vertical plane of the plate permits the plate under the pressure of the solution to have a slight rocking 60 movement on its lower edge, so that the small contacting points of the hanger will engage but one side of the plate at the same time. A further advantage, which follows 65 from the vertical arrangement of the plates in the hangers, resides in the agitation of

the solutions caused by the sidewise movement of the plates through the baths, so that such solutions are not permitted to precipitate, as is the case when the plates are dipped while suspended vertically, or are 70 passed edgewise through the baths while supported for horizontal movement, due to lack of agitation of the solutions when the plates are so moved.

The blanks are supplied in succession to 75 the hangers at the left hand end of the apparatus as indicated in Fig. 3. After traversing the several baths, the pickled plates are delivered at the right hand end of the apparatus. The length of the baths and the 80 time required for the movements of the metal plates therethrough in order to receive suitable treatment are factors which will determine the rate of speed at which the endless conveyor is to be operated. In the 85 mechanism disclosed in the patent hereinbefore referred to, the metal plates or blanks are automatically supplied to the hangers, and after treatment automatically delivered therefrom. In some instances it is desirable 90 to employ dripping plates 29, to bridge the space between the adjacent ends of the tanks, so that as the plates are being conveyed from one tank to another, the chemicals 95 dripping from such plates will flow back into the bath from which the plates have just been lifted.

When the time arrives for shutting down the operation of the apparatus, the movement of the plates then in transit through 100 the pickling baths must continue until all of such plates have been delivered from the baths. This is necessary in order that injury to the plates by reason of too long a submersion in the acids may be avoided. 105

Having thus described my invention, what I claim and desire to secure by Letters Patent of the United States, is:

1. In a machine for pickling metal plates, a pickling vat, a traveling conveyor supported and operated out of the plane of the vat and provided with a plurality of aligned pendant hangers, each having a hook for engaging and supporting the plate in vertical position by its lower edge in the movement 110 of the plate through the vat.

2. In a machine for pickling metal plates, a pickling vat, a traveling conveyor supported and operated out of the plane of the vat and provided with a plurality of aligned 120 pendant hangers, each having a hook for engaging and supporting the plate in vertical position by its lower edge in the movement of the plate through the vat, and a contacting point adjacent the side of the plate to 125 reduce to a minimum the area of engagement of the plate with the hangers.

3. In a machine for pickling metal plates, a pickling vat, a traveling conveyor supported and operated out of the plane of the 130

- vat and provided with a plurality of aligned pendant hangers, each having a hook for engaging and supporting the plate in vertical position by its lower edge in the movement of the plate through the vat, and contacting points adjacent the opposite sides of the plate to reduce to a minimum the area of engagement of the plate with the hangers.
4. In a machine for pickling metal plates, 10 a pickling vat, a traveling conveyor supported and operated out of the plane of the vat and provided with a plurality of aligned pendant hangers, each having a hook for engaging and supporting the plate in vertical position by its lower edge in the movement of the plate through the vat, and provided with projecting points on the hangers for engaging alternately the sides of the plate as the latter is rocked and prevent engagement 20 of the plate with the hangers except through such points and hook, whereby the area of engagement of the hangers with the plate during the pickling operation is reduced to a minimum.
5. In a machine for pickling metal plates, 25 a pickling vat, a traveling conveyor supported and operated out of the plane of the vat and provided with a plurality of aligned

pendant hangers, each having a hook for engaging and supporting the plate in vertical position by its lower edge in the movement of the plate through the vat, and provided with oppositely spaced contacting points for alternately engaging the sides of the plate as the latter is rocked on its lower edge while passing through the solution in the vat.

6. In a machine for pickling metal plates, a pickling vat, a traveling conveyor supported and operated out of the plane of the vat and provided with a plurality of aligned pendant hangers, each having a hook for engaging the lower edge of the plate and supporting it in vertical position, the form of the hook permitting the plate to rock on its lower edge to expose the entire side surfaces 45 of the plate to the action of the solution during the pickling operation.

In testimony whereof, I have signed my name at Milwaukee, Wisconsin, this 27th day 50 of March, 1922.

EDWARD W. BURGESS.
